(57) **CLAIM**

The ornamental design for a tissue cassette cover as shown and described.

DESCRIPTION

FIG. 1 is a perspective view of a tissue cassette cover, showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof in which the tissue cassette cover is open;

FIG. 9 is a perspective view thereof in which the tissue cassette cover is closed; and,

FIG. 10 is an enlarged view showing a portion of FIG. 8. The broken lines shown in FIGS. 8–9, drawn to indicate the environment surrounding the tissue cassette cover, form no part of the claimed design. The dot-dashed lines shown in FIGS. 8 and 10 are for the purpose of identifying an enlargement view and form no part of the claimed design.
